UNITED STATES PATENT OFFICE.

HAROLD W. SHONNARD, OF UPPER MONTCLAIR, NEW JERSEY, ASSIGNOR TO ELEVATOR SUPPLIES COMPANY, INC., OF HOBOKEN, NEW JERSEY, A CORPORATION OF NEW JERSEY.

ELEVATOR-CONTROL APPARATUS.

Original application filed February 9, 1926, Serial No. 86986. Divided and this application filed October 19, 1927. Serial No. 227,173.

The present invention relates to an improved form of automatic door closers for use in connection with the doors or gates used at the various floors along an elevator shaft, as well as to certain improvements in the apparatus for controlling the electric safety circuits largely used in elevator practice in connection with the doors at the various floors.

10 One of the objects of this invention is the provision of an improved type of electric switch and operating means therefor. This improved switch being of the type generally designated as a master switch, the function 15 of which is to control the opening and closing of a safety circuit controlling the operation of the elevator hoisting mechanism.

This application is a division of my former application Serial No. 86,986 filed February 20 9th, 1926, which matured into a Patent Number 1,649,989, November 22, 1927, and entitled Door operating means.

The invention is illustrated in a preferred embodiment by way of example in the accompanying drawings, wherein Figure 1 is a 25 view in elevation of a part of a door, with the closer and master interlock or safety switch, Figure 2 is a similar view of one side of the door when in open position, Figure 3 is an end view of the same and Figure 30 4 is a view in elevation on a larger scale of my preferred master safety switch.

In Figures 1 and 2 the two sliding doors at a given floor on an elevator shaft are shown 35 at 10 and 11. The door 10 is suspended from hangers 12 adapted to roll along the guide bar or rail 13.

Above the level of the doors and at one 40 side of the door opening is fixed the automatic door closer 14, preferably of the type in which the door closing element proper is combined with means for checking the final door movement in both opening and closing to prevent slamming. This is a well known 45 device the details of which are not a part of the present invention.

A supporting plate 15 is fixed to the outer 50 face of the door closer 14, and extends down along one side of the door opening, as shown to a point about opposite the middle of the doors 10 and 11.

The sliding back and forth of the door 10

is accomplished by means of the locking toggle arms 16 and 17, pivotally connected with the doors 10 and 19, and the arm 17 is similarly connected with and supported by the plates 15 and 20. An extension 21 of the arm 16 forms a handle whereby the toggle arms are manually brought into the position shown in Figure 2 in opening the door.

The closing of the door is accomplished in a well known manner by means within the closer 14, which act through the arm 22, and the connecting bar 23 pivotally attached at one end to the arm 24 fixed at the other to an arm 24 fixed to the toggle arm 17. When the door is opened, as in Figure 2, the swinging catch 25 may be brought under a stop 26 to lock the parts in open position, preventing 60 operation of the door closer.

As clearly shown in Figure 3, the sliding door 10, when in open position, moves under the door closer 14, and between the wall and the support plate 15. This is made possible by locating the supporting plate 15 on the 65 outer face of the door closer, as shown and described.

At the bottom of Figure 3 is shown the sill plate, and from inspection of the vertical dotted line in Figure 3, it will be seen that 70 my invention makes it possible for the doors and all the working parts connected therewith to be accommodated within a space inside of the shaft wall no wider than the sill 75 27.

The features of this mechanism just referred to form the subject matter of the 80 claims in my former application above referred to.

In many elevators, depending upon electric currents for operation it is customary to employ a master switch or interlock, generally 85 near the top of the shaft, which insures the shutting of all doors before starting the elevator cage, by keeping the operative circuit open until the doors are shut. These are 90 generally operated by a cable extending down alongside of the shaft and operatively connecting with a switch, the cable having a weight attached to it. If the cable breaks or the weight becomes detached, such a master switch will fail to operate.

One feature of my invention is a means for operating the master switch so contrived that if the cable breaks or the counterweight

on the cable is disconnected, the switch will automatically go to open circuit position and the elevator cannot be moved.

The switch 28 may be of any well known construction the details of which are not here shown, and it is operated by an arm 29 connected by a rod 30 with a grooved wheel 31 over which passes a cord or chain 32. This last is continued down past all the doors in the shaft and is kept taut by a weight 33.

It will be noted that the rod 30 is threaded at both ends so that it may be adjustably connected both with the arm 29 and the wheel 31. To further carry out this purpose nuts 30' are provided at one end of rod 30 where it is joined to the wheel 31 so as to permit the adjustment of the rod on the wheel after which the rod is made fast by means of the nuts 30'.

Opposite each door in the shaft, the cord, rope or chain 32 carries a ball 34, or equivalent device, capable of engaging with an arm 35 on the connecting bar 23 operated by the door closer. When the doors are closed, as in Figure 1, the arm 35 descends, permitting the weight 33 to move the cord, tape or chain downward and turn the wheel 31 so as to bring the arm 29 into the position shown in Figure 4, which closes circuit in the switch 30 and permits the elevator to move.

A counterweight 36, the purpose of which will appear later, is mounted on a rod 36' along which it may be adjusted and held in place by means of the bolt or screw 36". This construction permits of a changeable leverage for the counterweight so that no new weight need be used when the device is applied to different systems. The rod 36' is removably mounted on the wheel 31 by means of screws 36". This removable feature of the rod 36' on the wheel 31 allows the counterweight to be put in place or to be replaced whenever this is found necessary or advisable.

When the door is opened as in Figure 2, the arm 35 lifts the ball 34 and weight 33, allowing the weight 36 on the wheel 31 to turn said wheel clockwise and so bring the arm 29 into the position shown in Figure 2. This opens the circuit and prevents operation of the ele-

vator. The weight 36 has a smaller turning movement than the weight 33.

By attaching the weight 36 to the wheel 31, independently of the operating cord, tape or chain 32, said weight will act to open the circuit at the switch 28 automatically in case the cord or chain should become detached.

A variety of changes may be made in this apparatus without departing from the scope of my invention, which is not limited to the details herein shown and described; the invention herein protected being limited only to the extent of the express limitations set forth in the claims.

What I claim is:

1. In an elevator system, an electric switch adapted to control the operation of the car, a wheel, adjustable means connecting said wheel and switch, a weighted cable on said wheel having one end fastened thereto, means at the various floor of the elevator shaft adapted to operate the wheel and switch through said cable, and automatic means for moving the wheel and switch into safety position comprising a counterweight removably and adjustably mounted on said wheel.

2. In a system for an elevator adapted to travel past a plurality of landings, means for selectively controlling the door at each landing, means for preventing movement of the elevator when any one of said doors is open comprising a safety switch, means tending to move said switch to the open position including an arm for operating said switch, a wheel, an adjustable connection between said arm and wheel and an adjustable counterweight removably mounted on said wheel, counterbalancing means for normally preventing the effective operation of said last named means comprising a weighted cable passing around said wheel and having one end secured thereto, and means for rendering said counterbalancing means ineffective upon operation of said door controlling means.

Signed at Hoboken, in the county of Hudson and State of New Jersey, this 18th day of October, A. D. 1927.

HAROLD W. SHONNARD.
